UNITED STATES PATENT OFFICE.

LOUIS BAUMANN, OF OFFENBURG, GERMANY.

RAG-CUTTING MACHINE.

SPECIFICATION forming part of Letters Patent No. 286,373, dated October 9, 1883.

Application filed September 6, 1883. (No model.) Patented in Germany April 25, 1882, No. 20,328, and in Austria-Hungary September 12, 1882, No. 19,982.

To all whom it may concern:

Be it known that I, LOUIS BAUMANN, residing at Offenburg, in the Empire of Germany, have invented new and useful Improvements 5 in Rag-Cutting Machines, of which the following is a specification.

The object of my invention is to provide a new and improved machine for cutting rags very finely preparatory to converting them into paper-pulp.

The invention consists in a rag-cutting machine having a reciprocating knife which is connected by a pivoted link with the machine-frame, whereby an oscillatory reciprocating movement is given to the knife, which thus makes a vertical shearing cut.

The invention also consists in various parts and details and combinations of the same, as will be fully set forth and described hereinafter.

Reference is to be had to the accompanying drawings, forming part of this specification, in which similar letters of reference indicate corresponding parts in all the figures.

Figure 1 is a front elevation of my improved rag-cutting machine. Fig. 2 is a longitudinal elevation of the same. Fig. 3 is a detail cross-sectional elevation of part of the same.

The main shaft A is journaled in the top of 30 a standard, B, and in a bracket-arm, C, of the said standard, and between the standard and the end of the arm a loose and a fixed belt-pulley, D D', are mounted on the shaft, which is also provided with a fly-wheel, E. On one 35 end the shaft A is provided with a crank, F, on the pin of which the upper end of the T-shaped knife-beam G is fitted, the ends of the cross-piece of the knife-beam being guided by vertical guides H on the frame B. The knife J 40 is bolted to the knife-beam G. A connecting-link, K, is pivoted to the knife-beam G and to the frame B. The rags rest on a bed-plate, L, along the edge of which the knife J cuts. Directly above the bed-plate a feeding-roller, M, is journaled, which is grooved longitudinally, or provided with ribs, or roughened in 45 any suitable manner.

On one end of the shaft of the feed-roller M a ratchet-wheel, N, is mounted, with which a

pawl, O, is adapted to engage, which pawl is 50 pivoted in one end of a rocking lever, P, pivoted on the shaft of the feed-roller. To the opposite end of the lever P a connecting-rod, Q, is held adjustably, the upper end of which rod is held adjustably in a transverse 55 groove, R, in the flat surface of a bevel cog-wheel, S, engaging with a beveled cog-wheel, T, on that end of the shaft A opposite the one on which the crank F is fixed.

The operation is as follows: The crank F 60 gives the knife-beam a reciprocating movement and the link K gives it an oscillating movement, so that the knife-beam will have an oscillatory reciprocating movement, and will make a vertical cut which at the same 65 time is a shearing cut whereby the rags will be cut very finely and will not be torn, and the raising of dust will be avoided. The feed-roller M is revolved slightly after each cut, and feeds the rags the required distance to the 70 cutter. The feeding device can easily be adjusted to feed a greater or less length of the rags after each cut.

My improved rag-cutting machine requires 75 less power than the machines for a like purpose that have been used heretofore.

Having thus described my invention, I claim as new and desire to secure by Letters Patent—

1. A rag-cutting machine having a reciprocating knife-beam connected by a link with 80 the frame of the machine, whereby an oscillatory reciprocating motion is given to the knife, substantially as herein shown and described.

2. In a rag-cutting machine, the combination, with the driving-shaft A, of the knife-beam G, reciprocated by the same, and of the link K, pivoted to the frame of the machine and to the knife-beam, substantially as herein shown and described.

3. In a rag-cutting machine, the combination, with the standard B, of the shaft A, the knife-beam G, the link K, pivoted to the knife-beam and to the standard, and of the vertical-guides H, substantially as herein shown and described.

4. In a rag-cutter, the combination, with the shaft A, of the knife-beam G, worked from the same, and of the feed-roller M, also worked

from the shaft A, substantially as herein shown and described.

5. In a rag-cutting machine, the combination, with the shaft A and the knife-beam G, worked from the same, of the feed-roller M, the ratchet-wheel N, the lever P, the pawl O, the connecting-rod Q, and the bevel cog-wheels S and T, substantially as herein shown and described.

10 6. In a rag-cutting machine, the combination, with the shaft A and the knife-beam G, worked from the same, of the feed-roller M,

the ratchet-wheel N, the pawl O, the lever P, the bevel cog-wheels S and T, and the connecting-rod Q, held adjustably on the bevel cog-wheel T and on the lever P, substantially as herein shown and described. 15

In testimony whereof I have signed my name to this specification in the presence of two subscribing witnesses.

LOUIS BAUMANN.
